SHIFTING FULCRUM VALVE FOR ROCK DRILLS.

Application filed May 27, 1925. Serial No. 33,119.

This invention relates to fluid actuated rock drills, but more particularly to an improved plate valve having a shifting fulcrum.

A plate or disk valve of the current thrown type for rock drills or other uses for distributing pressure fluid has been found to operate satisfactorily and well by the proper provision of a comparatively large valve surface under or opposite which the pressure is dropped when the exhaust port is opened by the piston, so that the pressure of the live pressure fluid and the tendency of the pressure fluid to produce a current over the end of the valve quickly closes the valve.

One of the objects of the present invention is to automatically increase the valve area from which the pressure is largely removed, at the instant of time that such function is brought into operation. An oscillating valve, oscillating about a fixed fulcrum, has certain predetermined pressure areas throughout its operation, but by shifting the fulcrum to one side or the other as the valve oscillates, these areas are automatically varied on one side or the other of the fulcrum of the valve, and in addition the valve is automatically thrown out of balance so that greater leverage may be applied on the closing side to cause the valve to close more quickly. The valve is also prevented from fluttering.

Further objects of the invention will hereinafter appear and the invention is illustrated in the accompanying drawings, in which—

Figure 1 is a longitudinal sectional elevation partly broken away of so much of a rock drill as will serve to make the invention clear,

Figure 2 is a transverse sectional view on the line 2—2 of Figure 1 looking upwardly in the direction of the arrows, but the ports K and L underneath the valve have been shown in dot and dash lines to show that they are not seen but in order to indicate their shape, and

Figures 3 and 4 are detail transverse sectional views through the valve showing the operation of the shifting fulcrum.

Referring to the drawings, the cylinder A is provided with the piston B having the forward extension or shank C extending through the front cylinder sleeve D. The cylinder is provided with a free exhaust port E con-

trolled only by the piston and in this instance conveniently located in the position indicated centrally of the cylinder.

The valve F is arranged in the valve chamber G in the head block H and between the valve and the cylinder is located the cylinder head plate J having the inlet port K leading directly to the back end of the cylinder and the inlet port L communicating with the passage O in the cylinder leading to the inlet port P at the forward end of the cylinder.

The valve F, for convenience of illustration, is shown in the form of a thin flat disk circular in form and uniformly tapering on its upper or outer side from the median line or diameter Q to the periphery at each side R and S. The under or opposite side of the valve is provided with a central flat portion T extending between the points a and b indicated as lines in Figure 2. From the location of these lines a and b the valve is substantially uniformly tapered on both end surfaces and in opposite directions to the periphery at the ends R and S. The valve may or may not be undercut or recessed as indicated at c and d to lighten the valve.

In consequence of the valve construction described, the valve oscillates or rocks first on the fulcrum formed along the line a which is in effect a rib and then along the line or rib b as indicated in Figures 3 and 4 so that the fulcrum shifts from the point a to the point b and back again as the valve oscillates, and does not oscillate about a central or median line. In consequence the area of the surface, bounded by the fulcrum line a and the periphery S of the valve at one side of the fulcrum, is greater than the area bounded by the line a and the periphery R of the valve at the other side of the fulcrum in the position indicated in Figure 3 and this relative proportion of areas on opposite sides of the fulcrum is reversed in Figure 4, when the fulcrum changes to the line b.

The valve chamber G in the head block H is circular in form and sufficient clearance is provided between the valve and the walls of the chamber to permit free oscillation of the valve. The valve may be guided in any suitable manner as by means of the pins U seated in the plate J and extending into longitudinal sockets V in the valve remote from the fulcrum points with sufficient clearance to

permit freedom of movement of the valve, without interference or friction between the fulcrum points and the guiding means.

The back head W of the rock drill is provided with the throttle valve X controlling the supply of live pressure fluid to the valve chamber G. The machine is provided with a compression relief valve Y having the heads Z controlling the compression relief ports e and f for relieving the compression at the ends of the cylinder after the main exhaust E is closed. This valve Y is automatically actuated by means of the ports g and h.

In the operation of the device, let it be assumed that the piston is at the end of its forward stroke and traveling rearwardly as indicated in Figure 1. The live pressure fluid in the valve chamber G holds the valve in the position indicated and live pressure fluid is admitted over the periphery S of the valve to the inlet port P at the forward end of the cylinder to drive the piston rearwardly. After the piston closes the exhaust port E, compression in the rearward end of the cylinder is relieved through the compression relief port e. When the piston B overruns and again opens the exhaust port E to the forward end of the cylinder, the compression relief valve Y is thrown forward by pressure acting through the port g and since the forward end of the cylinder is then open to exhaust, the pressure is reduced or dropped beneath the valve F over the entire surface of the valve from its fulcrum to the periphery S so that the live pressure fluid on top of the valve and compression pressure underneath the opposite end of the valve causes the valve to oscillate first about the fulcrum a and then the fulcrum is shifted to the fulcrum b and the valve closes the inlet port L communicating with the front end of the cylinder. At the same time, the inlet port K to the rear end of the cylinder is opened and the piston starts on its forward stroke after which the cycle is repeated.

The valve has a shifting fulcrum because the fulcrum shifts from a to b and vice versa or in other words the valve may be said to have shifting fulcrums to increase the leverage exerted by the pressure fluid on the valve. This feature is accomplished by virtue of the fact that the fulcrums a and b are spaced from the center of the valve. The provision of a flat portion T between the fulcrums a and b insures stability of the valve in its neutral position and permits a more even action of the valve.

The clearance between the periphery R and

S of the valve and the walls of the head block H forming the valve casing, as stated, is sufficient to permit free oscillation of the valve, but is purposely not excessive, and as shown in the drawings, is small enough to appreciably choke or restrict the passage of live motive fluid in passing over the periphery of the valve. For this reason there will be a marked drop in the pressure underneath the raised side or wing of the valve as shown in Figure 1, when the piston overruns and opens the main exhaust port E on its rearward stroke. This drop in pressure occurs quickly because of throttling of the live motive fluid in passing over the periphery of the valve, and the pressure drop is effective underneath the valve to close the same by virtue of the pressure reducing effect on the air passing the valve.

We are not to be understood as limiting the invention to the precise form and details of construction shown in the drawings because the drawings are merely illustrative of one preferred means of obtaining a shifting fulcrum. Obviously, equivalent constructions may be devised by those skilled in the art without departing from the spirit of the invention as defined and claimed in the appended claims.

We claim:

1. A fluid actuated rock drill, comprising a cylinder and reciprocating piston, a cylinder exhaust port, a valve chest having a flat valve seat, a fluid actuated oscillating distributing valve in the form of a thin plate formed with a flattened central median portion and oppositely extending surfaces tapered with respect to said median portion, whereby the edges of said median portion form two fulcrums for the valve.

2. A fluid actuated rock drill, comprising a cylinder and reciprocating piston, a cylinder exhaust port, a valve chest having a flat valve seat, a fluid actuated oscillating distributing valve in the form of a thin plate formed with a flattened central median portion and oppositely extending surfaces tapered with respect to said median portion, whereby the edges of said median portions form two fulcrums for the valve, said valve having longitudinal sockets and pins in the valve seat extending into the sockets for guiding the valve.

In testimony whereof we have signed this specification.

LEWIS C. BAYLES.
FRED M. SLATER.
